Primary Examiner — Rashida C. Walshon(74) *Attorney, Agent, or Firm* — Quarles & Brady LLP(57) **CLAIM**

The ornamental design for a shoe, as shown and described.

DESCRIPTION

FIG. 1 is a top, right, and front perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1; and,

FIG. 7 is a bottom plan view of the shoe of FIG. 1.

The dash-dash-dash lines are included for the purpose of illustrating portions of the shoe that form no part of the claimed design. The dash-dash-dash broken lines within the shaded area represent disclaimed seam and stitch lines and form no part of the claimed design. The broken lines immediately adjacent to the shaded areas define the bounds of the claimed design and form no part thereof.
